DISTILLATION OF TAR TO PRODUCE HEAVY
CREOSOTE OIL

Joseph Zavernik, Englewood, N. J., assignor, by
mesne assignments, to Allied Chemical & Dye
Corporation, a corporation of New York

Application August 29, 1940, Serial No. 354,675

11 Claims. (Cl. 196—76)

This invention relates to an improved method of distilling tar to produce valuable creosote compositions. By "tar" is meant coal tar including coke oven tar, gas house tar, and coal tars obtained from the low temperature carbonization or gasification of coal and water gas tar.

Tars such as coke oven tar, gas house tar, or water gas tar, contain constituents which are readily decomposed or polymerized at the high temperatures encountered in tar distillation. Such decomposition or polymerization in ordinary tar distillation processes gives an unsatisfactory yield of distillate oil and an oil product having a high "coke residue" (as determined by American Society for Testing Materials Test D-168-27). In United States Patent No. 1,759,816, granted May 20, 1930, directed to a joint invention of A. A. MacCubbin and myself is disclosed a process of distilling tar to give increased yields of distillate oils and high melting point pitches. This process involves flowing the tar through a coil still to heat the tar without vaporization and introducing the heated tar into a flash box where a portion of the tar vaporizes, leaving a pitch residue which is subjected to a vacuum treatment for distillation of further oils. The vapors released in the flash box are passed to a fractional condenser and are progressively cooled to condense the vapors into the desired fractions, such as creosote oils, naphthalene and tar acid oils. Many millions of gallons of tar have been distilled commercially in accordance with the invention of this patent. In this distillation of tar, the vapors released in the flash box at elevated temperatures are cooled slowly, involving a considerable period of cooling time, substantially in excess of two minutes. While valuable creosoting oils meeting commercial specifications have been produced by the method of this patent, it has been found that this method at times results in the production of a heavy creosote oil containing a relatively high coke residue. By the expression "heavy creosote oil" is meant an oil of about about 90% boils above 300° C. To produce heavy creosote oils meeting specifications requiring low coke residue contents, it has been necessary to redistill the oil, with consequent loss of oil and expense and labor involved in the redistillation operation.

It is an object of this invention to distill tar in a simple and expeditious manner to produce a high yield of heavy creosote oil having a low coke residue and low free carbon content. Other objects and advantages of this invention will appear hereinafter.

In accordance with this invention a confined stream of tar is heated rapidly and under pressure to a temperature above 570° F., preferably to a temperature of about 780° to 800° F., while avoiding release of vapor, and the heated tar is

introduced into an expansion zone to effect vaporization of volatile portions of the tar. The released vapors leaving the expansion zone at a temperature above 570° F., and preferably from 760° to 790° F., are passed to a cooling and condensing zone and are cooled as quickly as possible to a temperature at which the heavy creosote oil constituents are condensed. Preferably the vapors passing through the condensing zone are made to flow through a series of relatively short horizontal paths while being cooled for condensation of heavy creosote oil, and the condensate is withdrawn from each path separately to remove the condensed heavy creosote oil from contact with the hot residual vapors substantially as rapidly as formed, thereby materially reducing the time during which the heavy creosote oil is subjected to temperatures above 570° F. However, the condensing zone may comprise a series of relatively long horizontal cooling paths, each path having two or more condensate outlets so that the flow path of the condensate within the hot shell of the condenser unit and in contact with the hot vapors is relatively short. The residual vapors at a temperature below 570° F. may be passed to a fractional condenser or fractionating column for separation into further fractions. I have found that the time factor, i. e., the time during which each particle of heavy creosote oil is subjected to temperatures above 570° F. should not exceed two minutes, and preferably should be less than ten seconds. Operation in accordance with these conditions, I have found gives a high yield of heavy creosote oil having a low "coke residue."

I have also found that the coke residue and free carbon content of the heavy creosote oil may be further reduced by condensing a portion of the vapors from the flash box, and returning that condensate to the flash box. The condensate removed from the vapors takes with it the "tar fog" which would normally be carried along and condense with the vapors, and thereby reduces the coke residue and free carbon content of the distillate oils.

The invention will be further described in connection with the accompanying drawing, in which Figure 1 is a diagrammatic showing of an arrangement of apparatus for the practice of the invention; and Figure 2 is a top plan view of the type of condenser unit preferred for the practice of the invention.

Figure 1 shows apparatus for carrying out the process of my invention comprising storage tanks 1 and 2 for the tar to be distilled, a continuous pipe coil still 3, flash box 4, condenser unit 5 for removal of "tar fog," and a condenser assembly 6 for condensation of heavy creosote oil. Tar to be distilled is pumped from either or both of tanks 1 and 2. Crude tar containing up to 6 per cent

of moisture, or dehydrated tar or a mixture of crude and dehydrated tar, may be distilled; preferably the tar contains from 2 to 3 per cent of moisture. The tar, usually a mixture, is forced through pipe 7 by pumps 8 and 9 to heat exchangers 30 and thence through a pipe to the condenser units 11 of the condenser assembly 6 and to condenser unit 5, where it passes in indirect heat exchange relation with the vapors in the respective condenser units, serves as a cooling medium, and receives a preliminary heating.

The tar is flowed through the condenser units 11 and 5 in an order which is the reverse of the order in which the vapors to be condensed pass through the units 5 and 11. From the condenser units 11 and 5, the tar flows to the pipe coil still 3 through supply pipe 12. Alternatively, crude tar may be pumped from one tank through pipe 28 which meets supply pipe 12. Tar flowing from condenser unit 5 through pipe 12 thus mixes with tar from pipe 28 before entering the pipe coil still 3. The quantity of tar pumped through the condensers 11 and 5 depends upon the degree of fractionation desired; the smaller the quantity of tar pumped, the sharper (narrower) the oil fractionation obtained. The tar, usually mixed, passes through the pipe coil still 3 rapidly and under pressure and is heated in the pipe coil still to a temperature above 570° F., preferably from 780° to 800° F., and passed through pipe 13 to the flash box 4, constituting an expansion zone, which is at a pressure lower than that in the still 3, and preferably at atmospheric pressure or approximately so. The rate of flow of the tar per square inch of internal transverse area of pipe exposed to heat is preferably equal to 0.5 to 1.5 cubic feet per minute; in other words the tar flows in cubic feet per minute at a rate equal to about 10 to 14 per cent of the cubical capacity in cubic feet of the pipe coil still. In the flash box 4 the oil content of the tar vaporizes, leaving pitch; and the pitch is withdrawn from the flash box, desirably to a vacuum box (not shown), where additional oils are distilled off leaving behind a high melting point pitch.

The oil vapors from the flash box 4 may next be passed rapidly through condenser unit 5 for "tar fog" removal. Where the tar was heated initially to a temperature of from 780° to 800° F., the temperature of the vapors is preferably reduced in the unit 5 to between 730° to 760° F., and a portion of the oil vapors, which may be from 1 to 3 per cent, preferably about 1.5 per cent based on tar distilled is condensed. This condensate flows back to the flash box 4 by gravity, carrying with it the "tar fog" removed from the vapors. The lower boiling portion of the condensate is reevaporized in the flash box 4 and passes again to the condensers.

The vapors from the "tar fog" removal condenser 5, or from the flash box 4 in case the unit 5 is not employed, are then flowed rapidly through the condenser units 11 of condenser assembly 6. Each unit 11 provides a relatively short horizontal condensate flow path, and the units are connected in the condenser assembly 6 to provide a condensing zone in which the vapors pass through each of the horizontal condensing paths in series. While the units 11 are shown arranged in a horizontal row, it is to be understood they may be arranged in vertical or slanted banks

provided each unit has an individual outlet so that the condensate does not flow through several units. The vapors are flowed at such rate through these condenser units that each particle 5 of the vapors passes from the flash box through the tar removal condenser 5 and the condenser assembly 6 in less than two minutes, and preferably less than ten seconds. The cooling capacity of the condenser units 11 is regulated in controlling the flow of tar or other cooling medium through the condenser units 11 so that the vapors from the flash box are cooled from an initial temperature of about 760° to 790° F. to a temperature below 570° F., say within the range 15 of 530° to 560° F., and preferably to a temperature of about 550° F., and the heavy creosote oil is condensed in passing through the units 11. The heavy creosote oil condensate flows counter to the flow of vapors in each condenser unit and 20 is withdrawn separately from each unit 11 so that the heavy creosote oil is removed from contact with the hot vapors and hot condenser shells in the condenser units 11 substantially immediately after formation. The heavy creosote oil 25 condensate from the separate units 11 flows through the three-way valves 14 to the condensate line 15. By manipulation of the valves 14 the condensate may be divided into three parts and 30 flowed through the lines 16 to the condensate receivers 17, or all of the condensate may be passed to any desired receiver 17.

I have found that the heavy creosote oil condensed in the condenser units 11 of the condenser assembly 6 under the conditions of operation outlined above contains less than 1.5 per cent coke residue, usually less than 1.0 per cent, as compared with as much as about 4.5 per cent obtained by methods heretofore in use. Uncondensed vapors of lower boiling oils are 40 withdrawn from the condenser assembly at 18 and may be subjected to any desired fractional condensation to obtain fractions such as light creosote oil, naphthalene, tar acid oil and light solvents.

45 In the practice of my invention I have found it desirable to employ a single condenser unit of the type shown in Figure 2 as the "tar fog" removal condenser unit 5, and a number of similar units arranged in series, with the vapor outlet of one unit connected to the vapor inlet of the succeeding unit, as the condenser units 11 of condenser assembly 6 for condensation of heavy creosote oil. Briefly, each condenser unit comprises a horizontally disposed substantial cylindrical shell 19 having a vapor inlet 20 and vapor outlet 21 located near opposite ends of the shell 19 to provide a path for the vapors through the shell 19 past two hairpin tubes 22 within the shell 19 which constitute the cooling surface of the condensing unit. These tubes 22 extend within the shell 19 parallel to the axis of the shell and are supplied with a cooling fluid, which is preferably the tar to be distilled, from the header 23. 55 The header is provided with a tar inlet 24 and a tar outlet 25 and is so constructed that the tar flows successively through the two hairpin tubes 22 of each condenser and then through outlet 25 to the next condenser of the series counter-current to the flow of vapors through the condensers. Depending on the length of the condenser unit, one or more liquid outlets 26 are disposed at the bottom of each shell 19 so that condensate formed in each shell flows along a relatively short path, preferably countercurrently

to the vapors, and is continuously discharged from the condenser substantially immediately after it is formed. The relatively large cooling surface and the relatively short condensate path to the individual outlets 26 of the shells render this type of unit particularly suitable for use in the present process.

The following example is illustrative of a preferred embodiment of the invention.

Example.—Crude tar (moisture content 3.6%) at a temperature of 170° F. is pumped by pump 9 through the pipe 7 to the condenser assembly 6 and "tar fog" remover condenser 5. The temperature of the tar is raised in passing through the heat exchangers 30 from 170° to 400° F. and in passing through the condensers 6 and 5 from 400° to 570° F., and the preheated tar is passed through supply pipe 12 to the pipe still 3. The preheated crude tar flowing through pipe 12 is mixed with dry tar pumped directly through pipe 28 into pipe 12 prior to entering the still 3. The mixture comprises 57 parts of preheated crude tar and 43 parts of dry tar. The tar mixture flows through the coils of the still 3 at a rate per minute equal to 12% of the cubical capacity of the still and is there heated to a temperature of 800° F. without substantial evolution of vapors. The heated tar is then discharged from the still 3 through pipe 13 to the flash box 4, where the oil content of the tar is flashed into vapor, leaving behind a pitch having a melting point of 245° F. (cube-in-air method), which is withdrawn and subjected to vacuum treatment. The vapors, together with entrained "tar fog," are passed through the condenser unit 5 wherein the temperature is reduced to 750° F. and 1.5 per cent of the vapors based on tar distilled are condensed to remove "tar fog" and the condensate is returned to the flash box carrying the removed tar with it. The vapors from the condenser 5 are then passed through the condenser assembly 6 wherein the temperature is reduced to 560° F. for condensation of the heavy creosote oil fraction. The time factor for the passage of vapor through the condenser unit 5 and condenser assembly 6 is about 4.5 seconds. The heavy creosote oil obtained from the units of the condenser assembly 6 has a boiling range of from 220° to above 400° C., less than 10% of which boils below 300° C. and at least 80% of which boils down below 400° C., and contains only 1.0 per cent coke residue.

Thus it will be seen the invention provides a novel process for effecting the distillation of tar in a simple, efficient and expeditious manner to obtain good yields of high quality heavy creosote oil without redistilling the oil. By condensing the heavy creosote oil from the tar distillate vapors while passing the vapors through the condensers, removing the creosote oil condensate from contact with the hot vapors and hot shells of the condensers substantially as soon as formed, and cooling the vapors passing through the condensing zone to a temperature below 570° F. in less than two minutes, the content of those constituents of the heavy creosote oil vapors, which constituents upon heating tend to polymerize and decompose, is greatly reduced with consequent reduction of the coke residue of the oil. Furthermore, the removal of "tar fog" from the vapors prior to condensation of the heavy creosote oil promotes the obtention of a product of low coke residue and low free carbon content.

Whereas the process has been described in connection with the production of high melting point pitch, the same process may be utilized to

yield low melting point pitch. Thus, for example, roofing pitch of 140°-150° F. melting point (cube-in-water method) and briquetting pitch of 170°-180° F. melting point (cube-in-air method) 5 may be produced by this process by heating the tar in the pipe coil still to temperatures of about 640° to 660° F. and about 700° to 720° F., respectively, and cooling the vapors to a temperature below 570° F. in less than two minutes to condense the heavy creosote oil.

Cast iron is the preferred metal from which the condenser is fabricated for use in the condensation of coal tar. For distillation of other materials other suitable metals resistant to corrosion may be used. It will be understood the condenser system is suitably insulated to prevent excessive cooling to obtain the desired degree of condensation and loss of heat to the atmosphere.

Since certain changes may be made without departing from the scope of the invention, e. g. the invention may be carried out in equipment other than that illustrated, it is intended that the above shall be interpreted in an illustrative and not in a limiting sense.

I claim:

1. A process of distilling tar to produce a heavy creosote oil having a low coke residue which comprises flowing tar in a confined stream, heating the stream of tar to a temperature above 570° F. but below 800° F. without substantial vaporization of the tar, introducing heated tar from the stream into an expansion zone to vaporize a portion of the oil content of the tar, flowing the vapors thus produced through a cooling zone to condense a portion of the vapors, passing the condensate thus formed to said expansion zone in contact with the vapors leaving said expansion zone, thereby returning to said expansion zone the condensate formed in the said cooling zone and the "tar fog" removed from the said vapors by the condensation of said vapors taking place in said cooling zone and the washing of the vapors with said condensate taking place as the said vapors and the said condensate flow respectively 35 in contact with each other from and to the said expansion zone, revaporizing the lower boiling portion of the condensate thus returned to the expansion zone and causing the vapors thus formed to flow with the first mentioned 40 vapors through the cooling zone, rapidly passing the vapors from the cooling zone through a condensing zone to condense heavy creosote oil vapors so that the time during which each particle of the heavy creosote oil vapors is subjected 45 to a temperature above about 570° F. does not exceed two minutes, and continuously withdrawing the heavy creosote oil thus condensed from contact with the vapors substantially immediately upon formation.
2. A process of distilling tar which comprises flowing tar in a confined stream, heating the stream of tar to a temperature above 570° F. but below 800° F. without substantial vaporization of the tar, introducing heated tar from the stream 50 to an expansion zone to vaporize portions of the oil content of the tar, flowing the vapors thus produced through a cooling zone to condense a portion of the vapors, passing the condensate thus formed to said expansion zone in contact with the vapors leaving said expansion zone, thereby returning to said expansion zone the condensate formed in the said cooling zone and the "tar fog" removed from the said vapors by the condensation of said vapors taking place in said 55 cooling zone and the washing of the vapors with

said condensate taking place as the said vapors and the said condensate flow respectively in contact with each other from and to the said expansion zone, revaporizing the lower boiling portion of the condensate thus returned to the expansion zone and causing the vapors thus formed to flow with the first mentioned vapors through the cooling zone, and passing the vapors from the cooling zone through a condensing zone.

3. The process of distilling tar to produce a heavy creosote oil having a low coke residue which comprises flowing tar in a confined stream, heating the stream of tar to a temperature of 640° to 660° F. without substantial vaporization of the tar, introducing heated tar from the stream into an expansion zone to vaporize a portion of the oil content of the tar, flowing the vapors thus produced through a cooling zone to condense a portion of the vapors, passing the condensate thus formed to said expansion zone in contact with the vapors leaving said expansion zone, thereby returning to said expansion zone the condensate formed in the said cooling zone and the "tar fog" removed from the said vapors by the condensation of said vapors taking place in said cooling zone and the washing of the vapors with said condensate taking place as the said vapors and the said condensate flow respectively in contact with each other from and to the said expansion zone, revaporizing the lower boiling portion of the condensate thus returned to the expansion zone and causing the vapors thus formed to flow with the first mentioned vapors through the cooling zone, rapidly passing the vapors from the cooling zone through a condensing zone to condense heavy creosote oil vapors so that the time during which each particle of heavy creosote oil vapors is subjected to a temperature above 570° F. does not exceed two minutes, and continuously withdrawing the heavy creosote oil thus condensed from contact with the vapors substantially immediately upon formation.

4. The process of distilling tar to produce a heavy creosote oil having a low coke residue which comprises flowing tar in a confined stream, heating the stream of tar to a temperature of 700° to 720° F. without substantial vaporization of the tar, introducing heated tar from the stream into an expansion zone to vaporize a portion of the oil content of the tar, flowing the vapors thus produced through a cooling zone to condense a portion of the vapors, passing the condensate thus formed to said expansion zone in contact with the vapors leaving said expansion zone, thereby returning to said expansion zone the condensate formed in the said cooling zone and the "tar fog" removed from the said vapors by the condensation of said vapors taking place in said cooling zone and the washing of the vapors with said condensate taking place as the said vapors and the said condensate flow respectively in contact with each other from and to the said expansion zone, revaporizing the lower boiling portion of the condensate thus returned to the expansion zone and causing the vapors thus formed to flow with the first mentioned vapors through the cooling zone, rapidly passing the vapors from the cooling zone through a condensing zone to condense heavy creosote oil vapors so that the time during which each particle of heavy creosote oil vapors is subjected to a temperature above 570° F. does not exceed two minutes, and continuously withdrawing the heavy creosote oil thus condensed from contact with the vapors substantially immediately upon formation.

5. A process of distilling tar to produce a heavy creosote oil having a low coke residue which comprises flowing tar in a confined stream, heating the stream of tar to a temperature above 570° F. but below 800° F. without substantial vaporization of the tar, introducing heated tar from the stream into an expansion zone to vaporize a portion of the oil content of the tar, flowing the vapors thus produced through a cooling zone to condense a portion of the vapors, passing the condensate thus formed to said expansion zone in contact with the vapors leaving said expansion zone, thereby returning to said expansion zone the condensate formed in the said cooling zone and the "tar fog" removed from the said vapors by the condensation of said vapors taking place in said cooling zone and the washing of the vapors with said condensate taking place as the said vapors and the said condensate flow respectively in contact with each other from and to the said expansion zone, revaporizing the lower boiling portion of the condensate thus returned to the expansion zone and causing the vapors thus formed to flow with the first mentioned vapors through the cooling zone, rapidly passing the vapors from the cooling zone through a series of paths to condense heavy creosote oil vapors so that the time during which each particle of the heavy creosote oil vapors is subjected to temperatures above about 570° F. does not exceed two minutes, and continuously withdrawing condensate from each path separately to remove the condensed heavy creosote oil from contact with the vapors substantially immediately upon formation.
35. 6. A process of distilling coal tar to produce a heavy creosote oil having a low coke residue which comprises flowing coal tar through a coil still to heat the tar to a temperature of about 780° to 800° F., introducing the heated tar into a vapor box to vaporize a portion of the oil content of the tar, flowing the vapors thus produced through a cooling zone to condense a portion of the vapors, passing the condensate thus formed to said vapor box in contact with the vapors leaving said vapor box, thereby returning to said vapor box the condensate formed in the said cooling zone and the "tar fog" removed from the said vapors by the condensation of said vapors taking place in said cooling zone and the washing of the vapors with said condensate taking place as the said vapors and the said condensate flow respectively in contact with each other from and to the said vapor box, revaporizing the lower boiling portion of the condensate thus returned to the vapor box and causing the vapors thus formed to flow with the first mentioned vapors through the cooling zone, rapidly passing the vapors from the cooling zone through a condensing zone to condense heavy creosote oil vapors, regulating the rate of flow and the rate of cooling of the vapors in the condensing zone so that the time during which each particle of the heavy creosote oil vapors is subjected to a temperature above about 570° F. does not exceed two minutes, and continuously withdrawing the heavy creosote oil thus condensed from contact with the vapors substantially immediately upon formation.
60. 7. A process of distilling coal tar which comprises flowing coal tar in a confined stream, heating the stream to a temperature of about 780° to 800° F. without substantial vaporization of the tar, introducing heated tar from the stream to an expansion zone to vaporize portions of the oil content of the tar, flowing the vapors from said zone to a cooling zone, removing "tar fog" from the

- 75.

vapors by cooling them to about 730° to 760° F. to condense from 1 to 3% of the vapors based on tar distilled during flow through the cooling zone, and passing the condensate formed to the expansion zone in contact with the vapors leaving said zone, thereby returning to said expansion zone the condensate formed by cooling the vapors to about 730° to 760° F. and the "tar fog" removed from the vapors by the condensation of said vapors and the washing of the vapors with said condensate taking place as the said vapors and the said condensate flow respectively in contact with each other from and to the said expansion zone, and revaporizing the lower boiling portion of the said condensate thus returned to the expansion zone and causing the vapors thus formed to flow with the first mentioned vapors through the cooling zone.

8. A process of distilling coal tar to produce a heavy creosote oil having a low coke residue which comprises flowing coal tar through a coil still to heat the tar to a temperature of between about 780° and about 800° F., introducing the heated tar into a vapor box to vaporize a portion of the oil content of the tar, flowing the vapors thus produced through a cooling zone to condense a portion of the vapors, passing the condensate thus formed to said vapor box in contact with the vapors leaving said vapor box, thereby returning to said vapor box the condensate formed in the said cooling zone and the "tar fog" removed from the said vapors by the condensation of said vapors taking place in said cooling zone and the washing of the vapors with said condensate taking place as the said vapors and the said condensate flow respectively in contact with each other from and to the said vapor box, revaporizing the lower boiling portion of the condensate thus returned to the vapor box and causing the vapors thus formed to flow with the first mentioned vapors through the cooling zone, rapidly passing the vapors from the cooling zone through a condensing zone to condense heavy creosote oil vapors, regulating the rate of flow and the rate of cooling of the vapors in the condensing zone so that the time during which each particle of the heavy creosote oil vapors is subjected to temperatures above about 570° F. does not exceed ten seconds, and continuously withdrawing the heavy creosote oil thus condensed from contact with the vapors substantially immediately upon formation.

9. A process of distilling coal tar to produce a heavy creosote oil having a low coke residue which comprises flowing coal tar through a coil still to heat the tar to a temperature of between about 780° and about 800° F., introducing the heated tar into a vapor box to vaporize a portion of the oil content of the tar, flowing the vapors thus produced through a cooling zone to condense a portion of the vapors, passing the condensate thus formed to said vapor box in contact with the vapors leaving said box, thereby returning to the vapor box the condensate formed in the said cooling zone and the "tar fog" removed from the said vapors by the condensation of said vapors taking place in said cooling zone and the washing of the vapors with said condensate taking place as the said vapors and the said condensate flow respectively in contact with each other from and to the said vapor box, revaporizing the lower boiling portion of the condensate thus returned to the vapor box and causing the vapors thus formed to flow with the first mentioned vapors through the cooling zone, rapidly passing the vapors from the cooling zone through a series of paths to condense

heavy creosote oil vapors regulating the rate of flow and the rate of cooling of the vapors in the paths of the condensing zone so that the time during which each particle of the heavy creosote oil vapors remains above a temperature of about 570° F. does not exceed ten seconds, and continuously withdrawing condensate from each path separately to remove the condensed heavy creosote oil from contact with the vapors substantially immediately upon formation.

10. A process of distilling tar to produce a heavy creosote oil having a low coke residue which comprises flowing tar in a confined stream, heating the stream of tar to a temperature above 570° F. but below 800° F. without substantial vaporization of the tar, introducing heated tar from the stream into an expansion zone to vaporize a substantial portion of the oil content of the tar, flowing the vapors from said expansion zone through a cooling zone, removing "tar fog" from the vapors by condensing a portion of the vapors during flow through the cooling zone, returning the condensate together with "tar fog" removed from the vapors to the expansion zone in contact with vapors leaving said zone, revaporizing the lower boiling portion of the condensate thus returned to the expansion zone and causing the vapors thus formed to flow with the first mentioned vapors through the aforesaid cooling zone, passing the vapors through a second cooling zone to condense heavy creosote oil vapors, regulating the rate of flow and the rate of cooling of the vapors in the first and second cooling zones so that the time during which each particle of the heavy creosote oil vapors is subjected to a temperature above about 570° F. does not exceed two minutes, and continuously withdrawing the condensed creosote oil from contact with the vapors in the second cooling zone substantially immediately upon formation.

11. A process of distilling coal tar to produce a heavy creosote oil having a low coke residue which comprises flowing coal tar in a confined stream, heating the stream of tar to a temperature between about 780° and about 800° F., without substantial vaporization of the tar, introducing heated tar from the stream into an expansion zone to vaporize a portion of the oil content of the tar, flowing the vapors from said expansion zone into a cooling zone, removing "tar fog" from the vapors by cooling the vapors in said cooling zone to a temperature of about 730° to about 760° F. to condense a portion of the vapors, returning the condensate together with "tar fog" removed from the vapors to the expansion zone in contact with vapors leaving said zone, revaporizing the lower boiling portion of the condensate thus returned to the expansion zone and causing the vapors thus formed to flow with the first mentioned vapors through the aforesaid cooling zone, passing the vapors to a second cooling zone, flowing the vapors in the second cooling zone through a series of cooling and condensing paths, regulating the rate of flow and the rate of cooling of the vapors in the first and second cooling zones so that each particle of the oil vapors is reduced to a temperature below about 570° F. in less than ten seconds to condense heavy creosote oil vapors, and continuously withdrawing condensate separately from each path of the second cooling zone to remove the condensed heavy creosote oil from contact with the vapors substantially immediately upon formation.
